CYCLIC CONTROL MEANS IN SELECTIVE PRINTING MACHINES

Carl J. Hueber, Euclid, Ohio, assignor to Addressograph-Multigraph Corporation, Wilmington, Del., a corporation of Delaware

Application November 8, 1946, Serial No. 708,784

14 Claims. (Cl. 101—58)

1

This invention relates to printing machines and particularly to such machines in which printing impressions are made from printing devices that are passed sequentially through the machine.

Printing machines of the aforesaid character are adapted for rapid operation to print impressions from at least selected printing devices as they reach printing position, and to attain maximum production, it is customary to provide automatic sheet feeding or positioning means that are arranged to feed or advance the sheets with respect to printing position to receive impressions in different locations on the sheet from successive printing devices. Such printing machines in many instances embody automatic control means, conventionally termed selector mechanism, whereby identifying means disposed at one or more selected identifying positions on the printing devices may be rendered effective to control operation of one or more of the various mechanisms of the printing machine. Thus selector mechanism in such printing machines has in the past been employed to render the impression mechanism, such as a platen, inoperative in respect to selected printing devices in accordance with the sensed presence or absence of such identifying means at one or more selected identifying positions thereon, thus to control the print-skip operation of the machine. In other instances the selector mechanism has been employed to control mechanisms for separating or segregating selected of the printing devices, or to govern a supplemental printing mechanism such as a numbering machine. As another example of the uses to which selector mechanism may be put in printing machines of the aforesaid character, my copending patent application Serial No. 487,078, filed May 15, 1943, now Patent No. 2,414,813, issued January 28, 1947, illustrates and claims a machine wherein selector means cooperate with the identifying means on the printing devices to govern the cut-off mechanism of the machine so as to print from different areas of the printing devices, and in such copending application the selector means are also operable to govern the sheet separating or feeding means as well as the sheet stop mechanism of the sheet feeding means, thereby to produce printed sheets having different amounts of printed matter thereon under control of identifying means carried on the printing devices.

Another class of work upon which the printing machines of the aforesaid character may be utilized is in the production of printed tax rolls wherein the name of a property owner and a

2

legal description of the property are printed on the tax roll in different columns on the sheet. In the preparation of such tax rolls, the name of the property owner and a description of his property may in some instances be carried upon a single or individual printing device, and the name and the description of property are printed in different columns by the performance of what may be termed a two-column listing operation. 5 In connection with such work, however, it has been found in practice that the name and the legal description cannot in many instances be carried upon a single printing device, and it has therefore been customary to carry a part of the legal description on the same printing device with the name of the owner, and to carry the balance of the legal description on one or more supplemental printing devices, which are in such an instance termed follower printing devices, the first of such printing devices in such a group being termed the lead printing device. In the prior patents of Walter T. Gollwitzer, No. 1,982,330, patented November 27, 1934, and No. 2,002,772, patented May 28, 1935, groups of lead 10 and follower printing devices are utilized, and there are of course individual printing devices which do not have follower plates grouped therewith which are interspersed with or between the groups of lead and follower printing devices. As 15 disclosed in the aforesaid Gollwitzer patents, the lead and follower printing devices are utilized in the preparation of tax rolls, but in accordance with the aforesaid Gollwitzer patents the structure and operation of the machine is in each 20 instance of such a character as to require a relatively complicated system of applying or locating the identifying means upon the printing devices, and to enable individual printing devices and groups of printing devices that are to be used 25 in tax roll work to be classified and identified 30 in a simple and more expeditious manner is the primary object of the present invention.

The machine illustrated in the first of the two aforesaid Gollwitzer patents has an arrangement 35 such that each of the follower plates must carry an identifying device or tab, and this identifying device is utilized in controlling the shifting movement of the sheet upon which the tax roll is being printed, and to enable the use of identifying 40 means on the follower printing devices to be eliminated in tax roll work is a further object 45 of the present invention.

It will be evident that in the preparation of tax rolls there are instances where the number 50 of lines remaining upon the sheet will be insuffi-

cient to accommodate all of the group of printing devices that is to be next printed, and in the aforesaid Gollwitzer patent means are provided which afford an indication as to the number of follower plates that are included in the group that is to be next printed, and in the use of such machine it has been customary and necessary for the operator to constantly watch the indicating means and compare the indication given thereby with the number of lines remaining upon the sheet that is being printed, and to enable this aspect of the operation to be eliminated is a further object of the invention. More specifically it is an object of the present invention to enable the number of follower printing devices in each group to be compared automatically with the number of lines remaining upon the sheet, and to stop the operation of the machine when an insufficient number of lines remain upon the sheet to accommodate all of the follower printing devices of the next group. A related object is to afford an indication in such an instance as to the reason why the machine has been stopped, thereby to indicate promptly to the operator that a new sheet must be mounted in position in the machine.

In my prior Patents Nos. 2,359,849, 2,359,850, and 2,359,851, there is disclosed a printing machine that is relatively simple in construction and which has been produced in great numbers and has gone into wide use, while in my prior Patent No. 2,359,853, patented October 10, 1944, there is disclosed a multiple-column lister for use in association with the printing machine disclosed in the first three of my aforesaid patents, and a further and related object of the present invention is to enable the printing machine and the multiple-column lister of my aforesaid patents to be utilized in the preparation of tax rolls. An object related to the foregoing is to accomplish such tax roll printing with the multiple-column lister and the printing machine of my aforesaid patents in such a way that high volume production may be obtained with the machine. A more specific object of the present invention is to incorporate selector mechanism in the printing machine of my aforesaid patents whereby the printing from such lead and follower printing devices may be controlled through the use of identifying means carried solely upon the individual printing devices and upon the lead printing devices of the groups.

Other objects of the invention are to simplify the preparation of tax rolls and like printed lists; to assure proper numbering of the items printed; to simplify the work of the attendant in the printing of such lists; and to coordinate the various printing means and the paper feeding means and printing device feeding means in such a way as to enable the primary mechanisms of my aforesaid patents to be utilized with but little change or modification.

Other and further objects of the present invention will be apparent from the following description and claims and are illustrated in the accompanying drawings which, by way of illustration, shows a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present

invention and the purview of the appended claims.

In the drawings:

Fig. 1 is a perspective view of a printing machine embodying the features of the invention;

Fig. 2 is a fragmentary plan view illustrating the lister mechanism of the machine;

Fig. 3 is a schematic view illustrating the way in which printed information is transferred from individual printing devices and from the printing devices of different sizes of groups of printing devices;

Fig. 4 is a fragmentary vertical sectional view illustrating the control for the lister operating mechanism;

Fig. 5 is a fragmentary perspective view illustrating the individual line spacing means of the lister;

Fig. 5A is a perspective view illustrating further details of the lister control mechanism with the parts in the positions occupied when the lister is connected for operation;

Fig. 5B is a view similar to 5A and showing the parts in the positions which they occupy when the lister cam is stopped;

Fig. 6 is a fragmentary vertical sectional view illustrating the platen mechanism and the numbering mechanism and the actuating means therefore;

Fig. 7 is a fragmentary plan view taken partially in section and illustrating the path of advancing movement of the printing devices;

Fig. 8 is a fragmentary plan view illustrating the numbering mechanism and the actuating means therefor;

Fig. 20 is a fragmentary side elevational view of the selector mechanism;

Figs. 21 to 26 are fragmentary end views illustrating various details of the selector mechanism, certain of these views being taken along corresponding lines indicated in Fig. 20 of the drawings;

Figs. 27 to 29 are detailed views of the three control cams of the selector mechanism;

Fig. 29A is a detail view of a position of the structure shown in Fig. 25; and

Fig. 30 is a schematic wiring diagram of the electrical connections embodied in the machine.

In the form chosen for disclosure herein, the invention is illustrated as embodied in a printing apparatus comprising a printing machine 100, Fig. 1, of the flat bed type having an automatic two-column lister mechanism 400 operatively associated therewith for shifting and advancing sheets S across and with respect to a printing position afforded on the table top of the machine. The printing machine 100 is of the general character illustrated in my prior Patent No. 2,359,850, patented October 10, 1944, and this machine comprises a desk-like frame 101 having a table top T over which the sheets S may have moved and positioned in the course of the production with the desired printed impressions on such a sheet. The printing machine 100 as herein shown is adapted to make printed impressions from printing devices D which are initially placed in a stack in an upstanding magazine M disposed near the right-hand rear corner of the table top T of the machine. These printing devices D are withdrawn one by one from the bottom of the supply magazine M and are advanced in a step by step manner through a sensing position and into a printing position, such printing position being defined in part by a platen mechanism P located over the table top forwardly and to the left of the magazine M. The printing device advancing means whereby the printing devices are advanced through the machine are illustrated and described in my aforesaid Patent No. 2,359,850, and reference may be had to such patent for details of construction and operation of such printing device advancing means.

The printing apparatus of the present invention is adapted to produce printed sheets such as the assessment roll S illustrated diagrammatically in Fig. 3 of the drawings, and this assessment roll may be printed from individual printing devices D and groups of printing devices that are passed through the machine. Thus in Fig. 3 of the drawings, an individual printing device D₁ is illustrated having a sheet metal frame 150 carrying upper and lower metallic printing plates 151 and 152 which are removably held in place on the frame 150 in the manner well known in the art. The frame 150 also has an index card 153 secured in place in a conventional manner between the upper edge of the frame 150 and the upper edge of the upper printing plate 151. The upper printing plate, in the case of an individual printing device such as the printing device D₁ is arranged to have the name and address of a property owner embossed thereon, as indicated by the letter N in Fig. 3, while the lower printing plate is arranged to carry an embossed text which constitutes the legal description of the property owned by the person whose name appears at N on upper printing plate 151. The descriptive text on the plate 152 of the printing device D₁ is identified as W₁.

When the name N and the text W₁ are to be printed from the individual printing device D₁, the name N is printed in a first printing operation in the first column of the sheet S, and then, after appropriate shifting movements of the sheet S relative to printing position, the legal description W₁ is printed in the same line of the sheet S but in the second column of the sheet. At the time when the description W₁ is printed in the second column of a particular line, an

item number 155 is printed in what may be termed the third column of the sheet S and in the same line with the name N and the description text W₁. This item number 155 is printed by a numbering mechanism as will hereinafter be described so that but one item number appears for each name that is printed in the first column of the sheet S.

As hereinbefore pointed out, the legal description of the property owned by a particular person may be of such length that it cannot be included on the plate 152 of an individual printing device, and in such circumstances, one or more follower printing devices are provided so that a group of printing devices is afforded as to such owner. Thus in Fig. 3 several groups of printing devices are illustrated, the first group of which includes a lead printing device 2D₁ and a single follower printing device 2D₂. The second group that is 10 illustrated in Fig. 3 includes a lead printing device 3D₁ and two follower printing devices which are identified as 3D₂ and 3D₃. Still another group of printing devices is illustrated in Fig. 3 and this group includes a lead printing device 4D₁ and three follower printing devices identified as 4D₂, 4D₃, and 4D₄ respectively.

When the lead printing device of a group, such for example as the lead printing device 2D₁, is to be printed upon a tax roll S, the name carried 20 on the upper printing plate of the printing device is printed in the first column, and the legal description carried on the lower printing plate of this lead printing device is printed in the second column of the sheet S, and the item or serial number 155 is similarly printed in the third column and in the same line as the name and legal description taken from this particular lead printing device. With respect however to the follower printing devices, the single impression that is to 30 be made from such follower printing device is made from the lower printing plate thereof, the area normally occupied by the upper printing plate being vacant if this is desired. The impression made from the follower printing device is made in the second column of the sheet S directly beneath, or in the next line below, the legal description that was taken from the preceding lead printing device or follower printing device. With respect to such impressions made 40 from the follower printing device of a group, it will be observed that the space in the third column of the sheet is left vacant. In other words, the serial number 155 is printed only in those lines in which impressions have been made from a lead printing device or from an individual printing device, and the manner in which this 50 is accomplished will be described in detail hereinafter.

The relationship of the embossed areas on the 60 various printing devices with respect to the areas of the sheet S in which impressions are made is diagrammatically illustrated in Fig. 3 of the drawings, and lines have been extended from the various printing plates of the printing devices to 70 the areas of the sheet S in which in the illustrated example, impressions are made from such printing plates.

Under and in accordance with the present invention, the control of the various functions of the printing apparatus is obtained through the use of identifying means carried on the individual printing devices and upon the lead printing devices of the groups. Thus the follower printing devices need not carry tabs when the printing apparatus of the present invention is em-

ployed. Thus each individual printing device and each lead printing device carries a shiftable or pivoted tab PS which may be shifted to different positions for use in governing the print-skip operation of the machine. The individual printing devices and the lead printing devices of the groups also carry identifying means that are indicative of the number of printing devices in the several groups. Thus the individual printing device D₁ carries a tab T₁ in a predetermined identifying position along its upper edge which indicates that this printing device is an individual printing device. Similarly, the lead printing device 2D₁ carries a tab T₂ in another predetermined position along its upper edge so as to indicate that this lead printing device relates to a group that includes but one follower printing device. The lead printing device 3D₁ carries a tab T₃ that is in still another position along the upper edge of the printing device, and this indicates that the printing device 3D₁ is the lead printing device of a group containing two follower printing devices. Finally, the lead printing device 4D₁ carries a tab T₄ in still another identifying position along the upper edge thereof so as to indicate that this printing device constitutes the lead printing device of a group that contains three follower printing devices.

The platen mechanism P, Fig. 6, as herein shown is of the geared roller type and the particular construction thereof is fully illustrated and described in my prior Patent No. 2,359,850, patented October 10, 1944, and reference may be made to such prior patent for details of construction and operation of the platen mechanism. The platen mechanism P is supported on or beneath the forward end of a relatively rigid printing frame 104 that is carried on the frame of the printing machine, and while the printing frame 104 might be of many different constructions, I prefer to employ a rigid printing frame such as that shown and claimed in my prior Patent No. 2,275,439, patented March 10, 1942. It will be observed that the printing frame 104 extends upwardly from the table top T at a point adjacent to the supply magazine M and extends upwardly and laterally at an angle of substantially 45° with respect to the forward edge of the printing machine to a point adjacent to the front of the machine, and at its forward end the printing frame 104 carries a head 105 beneath which the platen mechanism P is supported.

The platen mechanism P includes a platen roller PR which is carried upon and beneath a carriage C, the carriage C being mounted on the head 105 for reciprocating movement in a direction from front to rear of the machine. Such reciprocating movement is imparted to the carriage C through means including a rock shaft 106 mounted in the printing frame 104 in a horizontal position and parallel to the forward edge of the table top T, and this rock shaft 106 has an arm 107 extending downwardly therefrom and connected to the carriage C so as to operate the carriage through a reciprocating stroke when the rock shaft C is actuated through a rocking movement. The carriage C is thus operated through a reciprocating stroke each time a printing operation is to be performed, and at the end of such a reciprocating stroke, the carriage C is located in its rearward position shown in Fig. 6. The platen roller PR is supported beneath the carriage C for movement in a generally vertical direction between an upper inactive position and a lower or active position, and as described in

detail in my aforesaid Patent No. 2,359,849, the arrangement is such that the platen roller PR is disposed in its elevated inactive position when the carriage C is in the aforesaid rearward or rest position thereof. In the first half of a printing cycle of the machine, the carriage C is moved in a forward direction, and during this forward stroke of the carriage C, the platen roller PR is progressively lowered to its effective position, and it will be observed in Fig. 6 of the drawing that the platen roller PR has two platen faces PF₁ and PF₂ formed thereon, and as an incident to the movements of the carriage C, a geared connection 108 is effective to cause rotative movement of the platen roller PR. As will hereinafter be described in greater detail, such a geared connection may be controlled so that the platen faces PF₁ and PF₂ may be rendered selectively effective, and in the aforesaid forward movement of the carriage C, the platen face that is to be effective is selected and disposed in such a position that it is moved with a rolling action over the sheet S as the carriage C is moved in a rearward direction during the last half of the printing cycle of the machine. The area and location or extent of the platen faces PF₁ and PF₂ serves to determine what areas of the printing plates are to be effective to produce printed impressions, as will be evident upon consideration of my aforesaid Patent No. 2,359,849. It will be understood of course that an inked ribbon is interposed between the printing device D and the sheet S during the production of the printed impression on the sheet, and in the event that carbon copies are to be made, the additional sheets are arranged to have a suitable carbon paper associated therewith in the conventional manner.

As described in my aforesaid Patent No. 2,359,850 the printing machine 100 is adapted under some circumstances to be operated under control of a plurality of foot pedals 120, 121 and 122 which may be selectively depressed to initiate the type of machine cycle which is desired. The foot pedal 120 is normally termed the "skip pedal" of the machine, since momentary depression of this pedal initiates a cycle of operation of the printing device advancing means, and during such cycle the platen mechanism P remains inactive. The foot pedal 121 is conventionally termed the "repeat pedal" for momentary depression of this pedal initiates operation of the platen mechanism P while the printing device advancing means remains inactive. The foot pedal 122 is normally termed the "consecutive pedal" of the machine since momentary depression of this pedal serves to initiate concurrent cycles of operation of the printing device advancing means and the platen mechanism P. When the machine is operated through the use of the consecutive pedal 122, the printing device that has been disposed at printing position in the preceding cycle of operation is discharged into a collecting drawer J during the first half of the machine cycle, and a new printing device D is advanced into printing position. This takes place at the time when the platen carriage C is being moved through its forward or advancing stroke, and the printed impression from the new printing device is made during the last half of the machine cycle, or in other words, during the rearward stroke of the platen carriage C.

When the printing machine is being used, a power source such as an electric motor is constantly driven, and the motor is controlled by a

control plunger 110 that is mounted in a forward control panel of the printing machine frame. In many instances, as where an automatic listing mechanism 400 is associated with the printing machine, it is desirable to operate the machine constantly and automatically and this is accomplished through the use of an auto-stop mechanism that is controlled by a plunger 112 mounted in the control panel 111 of the machine. Such auto-stop mechanism is fully illustrated and described in my aforesaid Patent No. 2,359,850 and such mechanism is operable to cause continuous and automatic operation of the machine and to automatically stop the mechanism when any one of a number of undesired conditions occur in the machine, such for example as the exhaustion of the supply of printing devices D or the completion of the printing operations on a particular sheet S. The auto-stop mechanism includes a solenoid 113, Fig. 30, which when energized serves to stop the machine operation as described in my aforesaid Patent No. 2,359,850.

The two-column lister mechanism 400, Fig. 2 is in most of its structural aspects the same as the illustrated mechanism illustrated in my aforesaid Patent No. 2,359,853, and the lister includes a stationary frame 405 that has spaced and generally U-shaped members 406 connected to the rear face of the frame 101 and affording a clearance throat above the level of the table top T within which a mounting carriage 408 is supported for transverse reciprocation in a direction parallel to the forward edge of the table top T. Such a mounting for the carriage 408 is afforded by a pair of transverse mounting rails 409 that are extending rigidly between the two side members 406, and the carriage 408 is suspended from and guided by the rails 409 by means including rollers 410 as shown in Fig. 2 of the drawings.

The lister carriage 408 is relatively long and flat, as will be evident in Figs. 1, 2 and 5 of the drawings, and this carriage serves as a support for a paper holder 412 and the actuating and control means for such paper holder. The paper holder 412 includes paper clamps 413 which are operated by a handle 414 which is operable to release or to clamp the paper clamps 413 with respect to the upper edge of the sheet S. As described in my aforesaid Patent No. 2,359,853, the paper holder 412 is slidably supported in a guide channel 415 that is carried on the lower face of the carriage 408, for limited longitudinal sliding movement, and a flexible actuating rack 416, Fig. 30, is connected to the paper holder 412 and is extended rearwardly along the channel 415 so that the desired movements may be imparted to the paper holder 412. In attaining the desired movements of the paper holder 412 in a rearward or line spacing direction, means including a pawl carrier 418, Figs. 2 and 5, are mounted for limited reciprocating movement above the channel 415, and in such reciprocation, the pawl carrier 418 imparts line spacing movements to the paper holder. In this connection it should be observed that in a two-column listing operation, the paper or sheet S must be shifted laterally throughout what are termed "column spacing" movements, and must be shifted rearwardly in a line spacing direction, as well as in a forward or back spacing direction in order that the printed information derived from different portions of a printing device D may be disposed in properly related positions in the same line on the sheet. As pointed out in my aforesaid Patent No. 2,359,853, the pawl carrier 418 is utilized to impart line spacing

movements to the paper holder 412, while the movements of the channel 415 are utilized to impart back spacing movement to the paper holder. The lateral or column shifting movements of the sheet S are obtained of course by lateral shifting movements of the carriage 408 of the lister.

Thus as will be evident from a consideration of my aforesaid Patent No. 2,359,853, the reciprocating movements of the channel 415 are imparted thereto as an incident to the lateral shifting movements of the lister carriage 408 by means including a stationary and angularly disposed cam 420, while the required reciprocating movements of the pawl carrier 418 are normally imparted thereto as an incident to the lateral shifting movements of the lister carriage 408 by a stationary cam 421. The cam 421 has a relatively wide cam slot formed therein which has an effective rearwardly facing edge 421A, and a cam roller 422 disposed and the upper face of the pawl carrier 418 is normally urged forwardly into cooperating engagement with the surface 421A by a spring 423A. Thus in the course of transverse reciprocating movements of the lister carriage 408, the channel 415 and the pawl carrier 418 are moved through reciprocating movements which are effective in the manner described in my aforesaid Patent No. 2,359,853 to impart line spacing and back spacing movements to the paper holder in properly timed relation to the lateral or column shifting movements of the paper carriage. Thus the line spacing movements of the paper holder 412 and the back spacing movements thereof are normally obtained only during transverse reciprocation of the carriage 408 in its lateral or column spacing direction, and the width of the cam slot on the cam 421 enables line spacing movement of the paper holder 412 to be obtained when the paper holder 412 is in its right-hand position, Fig. 2, wherein the left-hand or second column of the sheet is disposed opposite the printing position.

To attain such line spacing of the paper holder while the carriage 408 remains stationary, a single revolution motor 423 is suspended beneath the carriage 408 as shown in Fig. 5. The motor 423 drives a cam 424 which acts on one end of a pivoted lever 425 to impart rocking movement thereto. The upper end of the lever 425 acts on a roller 418R fixed on the pawl carrier 418 so that upon rotation of the cam 424, the pawl carrier 418 is moved rearwardly so as to thereby actuate the paper holder 412 through a line spacing stroke. The motor 423 is of conventional construction and includes a full-revolution switch 423S, Fig. 30, which maintains the motor circuit until a complete revolution of the cam 424 has taken place. The control of the motor 423 is attained in a manner to be described hereinafter.

Normal column spacing or shifting movements of the lister carriage 408 are obtained by means including a drum cam 425, Figs. 2 and 4 which is driven in a two-to-one relationship from a control clutch 426, Fig. 4. The control clutch 426 is of the one-revolution type, hence in a one-revolution cycle of the clutch 426, the cam 425 is operable through one half of a revolution. Thus in a first one half revolution of the cam 425, the carriage 408 is shifted in one direction by means including an operating lever 427 and a link 428 while in the second one half

revolution of the cam 425, the lister carriage 403 is returned in an opposite direction.

As described in my aforesaid Patent No. 2,359,853, the one-revolution clutch 426, Fig. 4, is controlled by a plurality of stop levers pivotally mounted on a shaft 429 and including a stop lever 430. The stop lever 430 is effective when it is located in the active position of Fig. 4, to disengage the clutch 426, and as disclosed in my aforesaid patent, an additional stop lever which corresponds to the stop lever 580 in my aforesaid Patent No. 2,359,853 is arranged for operation from one of the stop levers of the platen clutch of the machine so that when the machine is to operate through a skip cycle in which the platen is inactive, the lister clutch, which is the clutch 426 in the present drawings, is similarly maintained, disengaged so that the lister 400 will not operate. A similar functional interrelation of the platen mechanism and the lister mechanism is utilized in the present machine but is attained electrically as will be hereinafter described in detail.

The stop lever 430 is the one which corresponds to the stop lever 580 of the aforesaid Hueber Patent No. 2,359,853, and this stop lever 430 of the present machine is arranged to render the lister 400 operative or inoperative. Thus, a control plunger 432 is provided in the control panel 111, and as shown in Figs. 4, 5A and 5B, the plunger 432 has a rod 433 extending rearwardly therefrom. At its rear end, the rod 432 has a laterally projecting end 434 that extends through a slot 435 in a relatively wide arm 436. The arm 436 is fixed to one end of the sleeve 437 that is mounted for rocking movement on a supporting shaft 438, and an arm 439 fixed to the other end of the sleeve 437 extends in a forward direction. It might be noted that the shaft 438 in the present machine serves merely as a support for the sleeve 437, and does not serve to accomplish selecting functions or the like. At its forward end the arm 439 has a link 440 pivotally connected thereto, and the upper end of the link 440 is pivoted at 441 to the rearwardly projecting arm 430A of the stop lever 430. The rod 433 has a spring 442 connected thereto at 443 and is extended rearwardly so that its rear end is connected to a pin 444 fixed on the wide arm 436. Thus the arm 436 is normally drawn in a forward direction so that the end 434 of the rod 433 is engaged with the rear end of the slot 435, and when it is desired to have the lister 400 operate, the plunger 432 is withdrawn in a forward direction so as to release the stop lever 430 as shown in Fig. 5A. With this arrangement, the lister 400 will normally operate through what may be termed a half cycle each time the platen mechanism P is operated, but in the event that the machine is to operate through a skip cycle, the lister clutch 426 will be maintained disengaged so as to prevent lateral shifting of the lister carriage 408, this suppression of the lister shifting operation being caused by the functional interrelation between the platen clutch and the lister clutch hereinabove mentioned.

In accordance with the present invention it is frequently desirable to have the lister mechanism 400 remain idle during those cycles of operation of the platen mechanism P in which impressions are to be made from follower printing devices, and the stop lever 430 is utilized for this purpose. As thus will be evident in Figs. 4, 5A and 5B, a solenoid 445 is mounted on the rear wall of the

frame 101 and the armature of the solenoid 445 is connected by a link 446 to the wide arm 436 so that when the solenoid 445 is energized, the wide arm 436 will be rocked to the left in Fig. 5A to the position shown in Figs. 4 and 5B. This causes the stop lever 430 to be shifted to its active position so as to thereby maintain the clutch 426 disengaged so long as the solenoid 445 remains energized. The manner in which the lister control 445 is energized at the proper time in the machine cycle will be described in detail hereinafter.

The clutch 426 is mounted on a main drive shaft 450 of the machine and this drive shaft 15 is driven through an operating cycle whenever any of the various functions of the machine are to take place. Thus the main drive shaft 450 also has a one-revolution clutch 455, Fig. 14, mounted thereon for operating the printing device advancing means of the machine, and a similar clutch 460, Fig. 6, is mounted on the shaft 450 for operating the platen mechanism P. The structure and relationship of the clutches 455 and 460 is described in detail in my aforesaid 20 Patent No. 2,359,850, and reference may be had to such patent for details of construction and operation. In Fig. 6 of the drawings, however, it will be observed that the driven member of the clutch 460 acts through a link 461 to impart 25 rocking movement to an arm 462 that is fixed on a transverse shaft 463 mounted in the lower arm 104L of the rigid printing frame 104. At its opposite end the shaft 463 has an arm 464 which is connected by a vertical link 465 to an arm 466 30 fixed on the rock shaft 106, and hence when the platen clutch 460 is engaged, it acts in its one-revolution cycle to impart a rocking movement to the shafts 463 and 106, thereby to operate the platen mechanism P through a printing cycle.

When the machine is set for automatic and continuous operation, the platen mechanism P operates in each cycle of the machine, with the exception however that where a printing device is to be skipped, the clutch 460 is held against engagement so as to thereby prevent operation of the platen mechanism P. Thus during automatic operation a stop lever 468 associated with the platen clutch 460 is normally shifted and held in a retracted or inactive position, but in 45 Fig. 6 of the drawings, this stop lever 468 is shown in an active position in order to show a second stop lever 470 that is associated with the platen clutch 460 and which is urged normally to a retracted position by a spring 471. Thus when 50 both of the stop levers 468 and 470 are in their retracted positions, the platen clutch 460 will remain engaged, but when a particular printing device is to be skipped, the stop lever 470 is 55 shifted to its active position by a solenoid 473 that has its armature connected to the rear end of the stop lever 470. As will hereinafter be described in detail, the skip solenoid 473 is energized only under such circumstances and at such time that lister control solenoid 445 is also energized, and hence when the skip solenoid 473 is 60 energized to produce skip operation, both the platen operation and the lister operation will be suppressed in such skip cycles of machine operation.

The clutch 455, Fig. 14, which operates the printing device advancing means has an eccentric associated therewith that is connected by a link 474 to a rocker 475 and this rocker 475 is fixed on a shaft 476 mounted on the lower arm 104L of the printing frame. The shaft 476 is

connected through an arm 477, Fig. 7, to the printing device advancing means in the initial and final printing device guideways, while a linkage 478 extended from the arm 477 transmits movement to the printing device advancing means in the transverse or intermediate printing device guideway. Such structure is fully illustrated and described in my prior Patent No. 2,359,850. The clutch 455 has a main control stop lever 480, Fig. 14, which in normal operation of the machine is held in an inactive position. An additional stop lever 481 is also provided in association with the clutch 455 and this stop lever 481 forms a part of the duplicator or multi-print mechanism of the machine, and this multi-print mechanism is fully illustrated and described in my aforesaid Patent No. 2,359,850. Such multi-print mechanism is however under the present invention arranged so that the setting of the multi-print mechanism may be automatically changed from a duplicate setting to a consecutive setting when this is required in the preparation of tax rolls and the like. Thus a ratchet and cam assembly 484 is provided in the same manner as in my aforesaid Patent No. 2,359,850, and a rocker 485 controlled by the cam and ratchet assembly 484 is effective to control the position of the stop lever 481 so as to shift the same back and forth between active and inactive positions in alternate cycles of operation of the platen mechanism P. Thus an operating pawl 487 is connected to an arm on the shaft 463 in the manner described in my aforesaid Patent 2,359,850 so as to be reciprocated in each cycle of operation of the platen mechanism. The pawl 487 is urged toward an upper or effective relation by a spring 488, and in such upper or effective position a pin 489 on the pawl 487 cooperates with the ratchet of the assembly 484 to advance this assembly in each cycle of operation of the platen mechanism. The pawl 487 may however be shifted downwardly to an inactive position by means of a control plate 490 which has a rearwardly extending arm 491 thereon that engages the pawl 487 and moves the same downwardly when the plate 490 has rocked from the position shown in Figs. 14 and 16 to the position shown in Fig. 17. The plate 490 is utilized under the present invention for thus rendering the pawl 487 inactive when a follower printing device is moved into printing position in the machine. In my aforesaid Patent No. 2,359,850, the duplicator mechanism is controlled by a plunger 495 that is disposed in the control panel 111 of the frame, and the control plunger 495 under the present invention is operatively associated with the control plate 490 through a yielding lost motion connection that enables the control plate 490 to be shifted from its inactive position to its active position without disturbing the setting of the control plunger 495. Thus the inner end of the plunger 495 has a downwardly extending arm 497 fixed rigidly thereto, and from the lower end of the arm 497 a lever 498 is extended upwardly. The lever 498 is pivoted at its lower end at 498A on the arm 497, while at its upper end the lever 498 is connected at 498B to a link 500 that extends rearwardly and is pivotally connected to the upper edge portion of the control plate 490. A spring 501 acting between the slide or plunger 495 and the link 500 acts normally to urge the link to the forward position shown in Figs. 14 and 16, this position being limited and determined by a bracket 502 fixed on the arm 497. Thus the control plunger 495 may be withdrawn

in an outward direction to the duplicate setting shown in Fig. 16, and the machine will then operate to make two printed impressions from each printing device that is moved into printing position. The lever 498 may however be rocked to the position shown in Fig. 17 and this is accomplished by a solenoid 510 that has its armature connected by link 511 to the lever 498. Thus when the solenoid 510 is energized, the plate 490 is shifted to its active position, Fig. 17, and this causes the pawl 487 to be rendered inactive. It has been pointed out hereinbefore that an item number or serial number 155, Fig. 3, is printed in the third column of the tax roll S opposite the impressions made from each of the individual printing devices and opposite the impressions made from each of the lead printing devices, and this is accomplished by a numbering mechanism 515 that is illustrated in Figs. 6 and 15 8 to 10 of the drawings. The numbering mechanism 515 is disposed just to the left of the printing position at which the printing device D is disposed, such printing position being in what may be termed the final guideway of the machine. 15 Such final guideway is defined by supporting rails 518 and 519, Fig. 8, and the numbering machine 515 is disposed just to the left of the left-hand rail 518 as will be evident in Figs. 6 and 8 to 10. The numbering machine embodies a series of 20 numbering wheels mounted within a mounting body 520, and this mounting body is in turn supported upon an elongated plate 521 that is pivotally supported at 522 on the rail 519. Thus the numbering wheels included in the body 520 25 may be raised to an operative printing position shown in Fig. 9, or may be lowered to an inactive position shown in Fig. 10, and this is accomplished by means including a rocking cam shaft 524, Figs. 6, 8, 9 and 10. The cam shaft 524 has 30 a flat portion that is so arranged that when this flat portion is in a horizontal position the numbering wheels 520 will be disposed in their lower or inactive position, Fig. 10. When the shaft 524 is rocked to the position shown in Figs. 6 and 9, 35 the numbering mechanism is raised to its active position of Fig. 9. Such operation of the cam shaft 524 is normally attained by operation of a control plunger 525 which is disposed in the front panel of the machine. The plunger 525 in the 40 present instance has a rod 526 extended rearwardly therefrom, and is connected to the cam shaft 524 by a yielding lost motion connection. Thus a tubular sleeve 527 is fixed in a horizontal position on the rear end of the rod 526, and 45 a rod 528 is slidably extended into the opposite end of the sleeve 527. The rear end of the rod 528 is pivotally connected to an arm 529 on the shaft 524, this arm extending in a generally upward direction so that movement of the rod 528 50 serves to rock the shaft 524. Pins 530 and 531 are extended downwardly from the rod 528 and the sleeve 527 respectively, and a spring 532 extended between the pins 530 and 531 serves normally to hold the lost motion connection in the 55 relationship shown in Fig. 11. Thus by withdrawal of the control plunger 525 from the position shown in Fig. 10 and the position shown in Fig. 9 the shaft 524 may be so rocked as to raise the numbering mechanism to its operative position. 60 In the operation of the present machine, it is desirable to lower the numbering mechanism to its inactive position whenever a follower printing device is disposed at printing position, and this is accomplished by a solenoid 535. Thus the 65 solenoid 535 has a link 536 extended upwardly 70 75

from the armature thereof, and the upper end of this link is pivoted to an arm 537 fixed on the rock shaft 524. Thus when the numbering machine is to be rendered inactive, the solenoid 535 is energized and the rock shaft 524 is rocked in a counterclockwise direction to the position shown in Fig. 10. When this is done, the rod 528 is withdrawn in a left-hand direction, Fig. 11, with respect to the sleeve 527, thereby to lower the numbering machine to its ineffective position while enabling the plunger 525 to remain in the set position of Fig. 9. When the solenoid 535 is deenergized the spring 532 immediately returns the rock shaft 524 to the position shown in Fig. 9 so as to thereby restore the numbering mechanism to its active position.

The numbering machine 520 is of course arranged so as to be advanced one number each time an impression is to be made from the numbering machine. Thus the numbering machine has an actuating slide 540, Fig. 8, which when actuated in a forward or right-hand direction, Fig. 8, will advance the numbering machine by one digit. The slide 540 is in the present case actuated by a plunger 541 mounted on the plate 521 in such a position as to extend beyond the rear or left-hand edge of the plate 521 as viewed in Figs. 8, 9 and 10. An actuating arm 542 is provided for operating the plunger 541, the arm 542 being fixed on one end of a rock shaft 543 that is supported beneath the side rail 519. The arm 542 has a laterally projecting ear 542E which constitutes the element which is adapted to engage and actuate the left-hand or rear end of the plunger 541, and the arrangement is such that the plunger 541 is disposed in the path of the ear 542E only when the numbering machine is in its operative position of Fig. 9. When the numbering machine is lowered to its inactive position, the tilting movement of the plate 521 serves to raise the rear end of the plunger 541 to a position somewhat above the ear 542E, as will be evident in Fig. 10 of the drawings. Hence, when the numbering machine is in its inactive position, a rocking movement of the arm 542 will be ineffective to operate the plunger 541, and under such a circumstance the setting of the numbering wheels will remain unchanged.

The rock shaft 543 is arranged to be actuated each time that there is a concurrent operation of the platen mechanism and the printing device advancing means. In accomplishing this, an arm 544 is fixed on the shaft 543 as will be evident in Figs. 6 and 8, and a link 545 is pivoted to the arm 544 so as to extend downwardly and rearwardly therefrom. At its lower end, the link 545 is bifurcated as at 545B so as to embrace the shaft 476. The left-hand bifurcation of the link 545 has a laterally extending arm 545A formed thereon, and when the shaft 476 is in its at rest position, a pin 547 carried on an arm 548 fixed on the shaft 476 is disposed in engagement with the arm 545A so as to thereby hold the link 545 against upward movement. In this connection, it will be observed that a spring 549 acting between the link 545 and the shaft 463 serves normally to urge the link 545 in an upward direction, thus tending to rock the shaft 543 in a clockwise direction Fig. 9. The shaft 463 also has an arm fixed thereon so as to extend downwardly and to the right in Fig. 6, and a pin 550 on this arm is so arranged that it engages a shoulder 545S on the link 545 when the shaft 463 is in its at rest or home position. Thus when the platen operating shaft 463 and

the operating shaft 476 of the printing device advancing means are concurrently operated, the link 545 is released for upward movement of its actuating spring 546, and the operating arm 542 for the numbering machine is thereby rocked to the right in Fig. 9 through an operating stroke. Return movements of the shafts 463 and 476 serve of course to return the link 545 to its normal position and to thereby return the operating lever 542. In the event that the machine is operated through a skip-cycle so that the platen operating shaft 463 remains at rest, the pin 550 will hold the link 545 against upward movement and hence the numbering mechanism 5 will not be advanced. Similarly, in a second printing operation on a printing device, in which the printing device advancing means remains stationary, the pin 547 will act to hold the link 545 against movement, and here again, the numbering mechanism 10 will not be advanced. Thus the advancing of the numbering wheels is controlled so that a proper serial number will be entered only in those lines wherein impressions have been made from an individual printing device or a lead printing device, and the numbering machine is disposed in its inactive position 15 so that impressions will not be made in any other of the lines of the tax roll.

It will be recognized that the printing operations from different portions of the printing devices require changes in the line cut-off of the platen mechanism P, and this is accomplished through the use of the automatic line cut-off mechanism disclosed in my prior Patent 2,359,849. 20 In my aforesaid patent, the platen faces PF1 and PF2 may be rendered alternately effective by shifting movement of the base rack 555 of the gearing 168 of the platen mechanism. Such shifting of the base rack 555 is accomplished through the use of a ratchet and cam assembly 556 that is disposed on the printing frame 104 just rearwardly of the head 105, as will be evident in Figs. 1, 6, 12 and 13. This ratchet and cam assembly 556 is arranged normally to be operated by a pawl 557 that is pivoted at 558 on the arm 101, Figs. 6, 12 and 13. The pawl 557 extends in a forward direction beneath the ratchet of the assembly 556, and the pawl is urged upwardly by a spring 559 so as 25 normally to tend to engage with this ratchet. Thus in each operating cycle of the platen mechanism P, the pawl 557 moves forwardly from the position shown in Fig. 13, thus normally to advance or index the cam and ratchet assembly 30 556 and thereby change the setting of the base rack 555. In the present machine, the arrangement is such that the operation of the cam and ratchet assembly 556 normally places the platen faces PF1 and PF2 in their operative positions 35 in alternate cycles of operation of the platen mechanism. It will be recognized however that when an impression has been made from the lower printing plate 152 of a lead printing device, the next impression will be made from the lower printing plate of a follower printing device, so that the setting of the platen mechanism must in such an event remain unchanged. 40 In order that this may be accomplished, a platen control solenoid 560 is mounted on the printing frame 104 directly above the pawl 557, and a pin 561 extended downwardly from the armature of the solenoid 560 is arranged to overlie the upper edge of the pawl 557. The solenoid 560 is so arranged that when it is energized, the pin 45 561 shifts the pawl 557 downwardly so that it will 45

not engage the ratchet of the ratchet and cam assembly 556. Because of this arrangement, the setting of the platen roller PR will remain the same in those cycles where an impression is to be made from a follower printing device. The solenoid 560 is controlled and energized in the manner hereinafter described.

As hereinbefore pointed out, the various functions of the present machine are controlled by sensing the identifying means such as the tabs carried on the individual printing devices and on the lead printing devices of the groups, and such sensing takes place at sensing station II, Fig. 7. In this connection it may be observed, that the printing devices are advanced along the printing device guideway shown in Fig. 7 from the supply magazine M, which is indicated as station I, to sensing station II in one cycle of the operation of the printing device advancing means. In the next cycle of operation of the printing device advancing means, a particular printing device is advanced first from sensing station II into a transfer station III, and in this same cycle is moved along the lateral or transverse portion of the printing device guideway into an intermediate or idle station III. In the next cycle of operation of the printing device advancing means, such a printing device is advanced to another idle station IV along the transverse printing device guideway, as shown in Fig. 7 of the drawings. The next cycle of operation of the printing device advancing means advances the printing device to a transfer station IVT that is afforded at the intersection of the transverse guideway and the final printing device guideway. In the next cycle of operation the printing device is advanced to station V which constitutes the printing station of the machine, while in the next cycle of the operation the printing device is advanced in a forward direction so as to be discharged in the collecting drawer J.

As each printing device is located at sensing station II, the identifying means thereof are sensed by a downward movement of a sensing head H, Figs. 7 and 19, and the sensing head H is of the same form and is operated in the same manner as the sensing head illustrated and described in my prior Patent No. 2,359,851. Thus the sensing head H comprises a horizontal bar 565 that is supported for vertical movement by a pair of vertical guide rods 566 and 567, such guide rods being slidably associated with rails 568 and 569 that form the initial printing device guideway. The sensing head H includes a pin bar 570 that is removably disposed on the bar 565 and which is adapted to carry sensing pins in selected positions for cooperation with the tabs of the printing device that is located at sensing station II. The sensing head H is moved downwardly during the last half of the cycle of operation of the printing device advancing means by means including a pair of vertical links 571, Fig. 19. Such links being operatively associated with a rocker 572, Fig. 20, in the manner disclosed in my aforesaid Patent No. 2,359,851. In such patent the mechanism is illustrated that is associated with a rod or link 573, Fig. 20, such mechanism being operable to urge the sensing head H upwardly in a positive manner and downwardly with a yielding force, and the arrangement is such that the sensing head moves downwardly through a sensing stroke in the last half of the cycle of the operation of the printing device advancing means. Thus the sensing head

H is effective to sense the identifying means carried by a particular printing device while such printing device is stationarily disposed at sensing station II.

5 The yieldingly induced downward movement of the sensing head H is utilized to sense the tabs carried by the printing device disposed at sensing station, and it is the extent of such downward movement that is the determining factor in 10 effecting the control operations that are to result from a particular tab carried by a printing device. Thus a sensing pin 575S is disposed on the pin bar 570 in such a position that it will engage a tab PS that is located in its left hand or skip position, and the skip pin 575S is relatively long as will be evident in Fig. 19. Hence when the skip 575S engages a tab PS that is in the skip position, the downward movement of the sensing head H will be stopped at a relatively high level 15 and the downward movement to the position or level thus determined is utilized as will herein-after be described to set up storage means which in turn become effective when the particular printing device that has been sensed is about to move into printing position V.

The other sensing pins that are employed are progressively shorter in length so that as herein shown the downward sensing movement of the sensing head H may be terminated at four other 20 levels that are progressively lower than the level determined by the sensing pin 575S. Thus a sensing pin 575-1 is disposed on the pin bar 570 in a position wherein it will engage a tab T-1 carried by an individual printing device, and this 25 pin 575-1 is the shortest of the sensing pins that are employed so that the sensing head will move to its lowest controlling level when the pin 575-1 is effective to stop the downward movement of the sensing head. Sensing pins 575-2, 575-3 30 and 575-4 are mounted on the sensing bar 570 in positions for engagement respectively with tabs T-2, T-3 and T-4, and these pins are progressively longer than the pin 575-1 so that 35 the sensing head H will move to different and progressively higher levels when tabs T-2, T-3 or T-4 are sensed. Such downward movements of the sensing head H are utilized to set up storage plungers 580 that are mounted for longitudinally setting movement, Figs. 18, 20 and 23 40 on a storage drum 581. The storage drum 581 is of the general character illustrated in my aforesaid prior Patent 2,359,851, but this storage drum 581 has twelve storage plungers 580 disposed at equally spaced points about its periphery as disclosed in my aforesaid copending application Serial No. 487,078. The storage drum 581 is carried on a shaft 582 that is supported in a bearing casting 583, Figs. 18 and 20, and the casting 583 is in turn supported upon a mounting plate 584 that extends in a downward direction from the rail 569 of the initial printing device guideway. The shaft 582 has a ratchet 587 fixed thereon in such a position that it may be engaged and actuated by a pawl 588, Fig. 19. 45 The pawl 588 is carried on the arm 471 of the printing device advancing means as shown in Fig. 19 of the drawings, and as illustrated and described in my aforesaid prior Patent 2,359,851, the pawl 488 is effective in the first half of the 50 cycle of operation of the printing device advancing means, and during the time when a printing device is being advanced into sensing station, to impart an indexing movement to the storage drum 581. It should be pointed out in 55 this regard that the indexing movement of the

storage drum 581 starts almost immediately when the cycle of operation of the printing device advancing means is initiated.

The storage drum 581 is indexed in a clockwise direction, Fig. 20, and as the plungers are moved downwardly along the right-hand side of the drum, they are restored in an endwise direction to positions corresponding to the lowermost plunger 580, in Fig. 18. When a plunger 580 reaches the lowermost position on the drum, it is disposed in what may be termed the setup position of the drum, and in Fig. 20, this position has been indicated as station II, and the positions on the storage drum, progressively in a clockwise direction from the lowermost position, have been designated as stations III, IV, IVT, V, VI, VII and VIII. When a properly restored plunger is thus disposed in the setup station II, the sensing movement of the sensing head H is effective to set the plunger 580 to any one of a plurality of set positions in accordance with the location of the tab that has been sensed by the sensing head H. For this purpose, a setup arm 590 is pivoted on a vertical axis in a stationary casting 592, and this setup arm is swingable about its pivotal axis so as to engage a stud 593, Fig. 18, with the adjacent end of the storage plunger 580 that is located in setup position. The setup movements of the arm 590 are controlled from the sensing head H by a cam 595 that is adjustably connected by a turn buckle 596 to the lower end of the mounting rod 567. The cam 595 is guided in the casting 592 in a manner that is fully disclosed in my aforesaid Patent No. 2,359,851, and the swinging movements of the setup arm 590 are governed by engagement of a cam roller 596 on the arm 590 with a cam surface 597 on the cam 595. As an example of the operation of this setup mechanism, the downward movement of the sensing head H to a level that is determined by engagement of the skip pin 575S with a tab PS will serve to operate the arm 590 in such a way as to shift the storage plunger one space to the left in Fig. 18, or to the right as viewed in Fig. 23, into the skip position indicated in Fig. 23. When the downward sensing movement of the sensing head H is determined by engagement of a pin 576-4 with the tab T-4 of an individual printing device, the plunger will be moved two spaces, while the sensing of a tab T-3 will move the plunger three spaces. Sensing of a tab T-2 will cause the storage plunger to be moved four spaces, while sensing of a tab T-1 will cause the storage plunger to be moved five spaces to the individual setting indicated in Fig. 23.

The selective setting of the storage plungers 580 to different positions in accordance with the character or position of the tab on the respective printing devices enables such plungers to effectually control the operations or functions of the machine when the respective printing devices reach printing position, and under and in accordance with the present invention the sensing of the tabs of the lead printing devices serves to control the operations of the machine not only with respect to such lead printing devices, but also with respect to all of the follower printing devices that are related to such lead printing devices. In attaining such control of the mechanisms and functions of the machine, electrical switch means are afforded in an operative association with the several mechanisms and with respect to the storage drum 581 so that the se-

lective positioning or setting of the storage plungers may operate such switching means in definite ways to attain different sequences of operation as required by the character of the printing devices that are moved into printing position. Thus as will be evident in Figs. 20 and 30 of the drawings, a switch 601 is provided for controlling the print-skip operation of the machine, and a switch 602 is provided for controlling the lateral shifting movements of the two-column lister 400, while a switch 603 is provided for concurrently controlling the operation of the platen cutoff control, or duplicator control, the line spacing control of the lister, and the numbering machine control. The switches 601, 602 and 603 are of the micro-switch type and are supported on the mounting plate 584 by brackets 601B, 602B and 603B, respectively, so as to be disposed in spaced relationship about the left-hand side of the storage drum as viewed in Fig. 20.

The switch 601 that controls the print-skip operation of the machine is of the latching type which may be moved to a closed position by a lever 601L, and in order to again open the switch 601A, a restoring plunger 601P must be actuated. The switch 602 is of the normally closed type and may be opened by actuation of a lever 602L, and upon release of the lever 602L, the switch 602 will again be closed. The switch 603 is of the normally open type, and may be closed by actuation of a lever 603L. Upon release of the lever 603L, the switch 603 will again move to its open position.

The circuit connections for the various switches are diagrammatically illustrated in Fig. 30 of the drawings, and as a preliminary to the description of the structure for actuating the various switches, certain of these circuit connections will be described. Thus a source of electric current is indicated in Fig. 30 as constituting a battery 605 from one terminal of which wires 606, 607, 608 and 609 are extended in a series to one terminal of the lister control solenoid 445. A wire 609 extends from the other terminal of the solenoid 445 to one contact of the normally closed switch 602, while wires 610 and 611 in a series extend from the other contact of the switch 602 to the other terminal of the battery 605. Thus the lister control solenoid 445 will be energized and the lister drive clutch 426 will be held disengaged so long as the switch 602 remains in its normal closed position, and as will be described in detail hereinafter, the switch 602 is opened so as to release the clutch 426 in those cycles of machine operation where lateral shifting movement of the lister carriage 403 is desired.

The skip control solenoid 473 has one of its terminals connected to a wire 613 that is extended to the wire 607A, thereby to connect the solenoid 473 to one side of the electrical source. A wire 614 extends from the other terminal of the solenoid 473 to one contact of the switch 601, while a wire 615 is extended from the other contact of the switch 601 to the wire 611. Thus upon closure of the switch 601, the skip solenoid 473 is energized and the platen mechanism P will be held against operation. When the skip switch 601 is thus closed so as to cause a particular printing device to be skipped, it is also desirable that the lister 400 be maintained inoperative, and this is accomplished by the switch 602, which by reason of its normally closed relation, prevents lateral shifting of the lister carriage in all cycles of machine operation except those cycles in which

a lead printing device or an individual printing device that is to be printed is moved into printing position. This inherent characteristic of the machine will become evident as the description proceeds.

The switch 603, Figs. 20 and 30, has one terminal thereof connected to the wire 611 by the wire 619, while a wire 620 connects the other terminal of the switch 603 to one terminal of the control solenoid 535 of the numbering machine. Wires 621 and 622 in series are extended from the other terminal of the solenoid 535 and the wire 607 thus to place the solenoid 535 in an energizing circuit controlled by the switch 603. A wire 623 extends from the wire 622 to one terminal of the line space motor 423, and branch leads 624 and 625 from the wire 623 are connected respectively to one terminal of the platen control solenoid 560 and one terminal of the duplicator control 510. Another wire 627 is extended from the wire 620 to one terminal of the line space motor 423, and branch leads 628, and 629 are extended respectively to the other terminal of the platen control solenoid 560 and one terminal of the duplicator control 510. Another wire 627 is extended from the wire 620 to one terminal of the line space motor 423, and branch leads 628, and 629 are extended respectively to the other terminal of the platen control solenoid 560 and the other terminal of the duplicator control solenoid 510. Thus the solenoids 510 and 560 and the motor 423 are also placed under the control of the switch 603. It will be recalled that the motor 423 has a full revolution switch 423S, and this switch is connected in parallel with the switch 603 by means including a wire 630.

Returning now to the manner in which the switches 601, 602 and 603 are actuated under control of the storage plungers 580, it will be observed that a mounting casting 635 is mounted on the plate 584 adjacent to the left hand side of the storage drum 581 as viewed in Fig. 20, and this mounting casting 635 has three pivot studs 636, 637 and 638 mounted thereon so as to extend parallel to the rotative axis of the storage drum 581. The mounting stud 636 has five transmitting levers 640 mounted thereon for rocking movement, and these levers 640 are urged in a clockwise direction to positions determined by a stop pin 640X by individual springs 640R that are anchored on a projecting anchoring stud 640P. When any one of the transmitting levers 640 is rocked slightly in a counter clockwise direction Fig. 20 from the position shown, such lever is arranged to have a particular controlling action. The five transmitting levers 640 are of a generally similar form and are disposed side by side along the mounting stud 636 in such a relation that the different transmitting levers will be engaged by the cam lobes 580C of the storage plungers 580 in accordance with the setting of such storage plungers. The transmitting lever 640 that is disposed closest to the mounting plate 584 is identified in Figs. 21 and 24 as lever 640S, and this transmitting lever 640S, functions only in setting the skip switch 601 to its closed position as will hereinafter be described. The next lever on the mounting stud 636 is identified as lever 640-4 in that this lever is aligned with the position which will be occupied by the cam lobe 580C of a storage plunger 680 that has been set in response to the sensing of a tab T-4. The next transmitting lever on the stud 636 is identified in Fig. 24 as lever 640-3 and this lever is positioned in alignment with the position that

will be occupied by the cam lobe 580C of a storage plunger 580 that has been set in response to the setting of a tab T-3. The next transmitting lever on the stud 636 is identified as lever 640-2 and this lever is so disposed that it is arranged for cooperation with the cam lobe of a storage plunger that has been set in response to the sensing of a tab T-2. The next or outermost transmitting lever on the stud 636 is identified in Fig. 24 as lever 640-1, and this transmitting lever is so disposed that it will cooperate with the cam lobe 580C of a storage plunger 580 that has been set in response to the sensing of a tab T-1 of an individual printing device. The manner in which the various levers 640 cooperate with and are actuated by such storage plungers 580 will be described in greater detail hereinafter.

The mounting stud 637 serves, as will be evident in Fig. 26 of the drawings, to support a relatively wide transmitting lever 645 which has a cam surface 645A formed on the outer or left hand end thereof as shown in Fig. 20. A spring 645R serves to urge the lever 645 in a clockwise direction, Fig. 20, to a normal position that is determined by a stop pin 646, the spring 645 being anchored on a pin 645P. When the lever 645 is rocked slightly in a counterclockwise direction Fig. 20, it serves to actuate the lever 602L so as to open the switch 602 and thereby release the lister drive clutch 426 which will then impart timed lateral shifting movements to the lister carriage 408.

The mounting stud 638 serves to support three transmitting cams 648-2, 648-3 and 648-4, the detailed form of which is shown in Figs. 27 to 29 of the drawings. The cam 648-2 is disposed for cooperation with the cam lobe 580C of a storage plunger 580 that has been set in response to the sensing of a tab T-2. The cam plate 648-3 is disposed in such a plane that it will cooperate with the cam lobe of a storage plunger that has been set in response to the sensing of a tab T-3; while the cam plate 648-4 is disposed in such a plane that it will cooperate with the cam lobe of a storage plunger that has been set in response to the sensing of a tab T-4. The several cam plates 648 are urged in a clockwise direction by individual return springs 648R that are anchored on a pin 648P, and such return movements are limited by a stop pin 649 that extends through slots 650 formed in several cam plates. The several cam plates 648 have cam surfaces 648A formed thereon at their left hand edges, Figs. 27 to 29, so that when any one of the cam plates 648 is rocked slightly in a counterclockwise direction from its normal or home position, the cam 648A thereof will engage and actuate an operating lever 603L so as to close the control switch 603.

The transmitting levers 640 are so disposed with relation to the storage drum 581 that these levers will be selectively rocked through a counterclockwise operating stroke when an appropriately set storage plunger 580 moves into station IVT of the storage drum, and when so actuated, such a lever 640 will remain in its actuated position until the next cycle of indexing movement of the storage drum 581 has been initiated. This is accomplished by affording similar projecting arms or extensions 640E on the levers 640 that extend as shown in Fig. 20 in a generally right hand and upward direction from the supporting stud 636.

When the transmitting lever 640S is thus actu-

ated by an appropriately set storage plunger 580, a cam extension 648A on the left hand end of this lever engages the lever 601L so as to close the skip switch 601, and it will be recalled that the switch 601 remains in its closed position until the operating plunger 601P of the switch is actuated. Thus a lever 652 is pivoted at 653 in position for engagement with the plunger 601P, and a restoring lever 654 pivoted at 655 has a cam slot 655S therein which engages a pin 652P fixed on the lever 652. The other end of the lever 653 has a pin 656 extended therefrom so as to be disposed beneath the lower edge of all of the levers 640. With respect to the lever 640S, however, the pin 656 is slotted as at 656S, Fig. 29A, so that operation of the lever 640S may be accomplished without actuating the pin 656 of the switch restoring lever 654. Operation of any other one of the levers 640 will however cause such lever to engage the pin 656 and thereby operate the restoring plunger 601P to again open the switch 601. The levers 640—2, 640—3 and 640—4 also serve to selectively close switches 660—2, 660—3, and 660—4 which are shown in Figs. 20 and 30 of the drawings, and the function of the several switches 660 will be hereinafter described in detail.

The wide lever 645 is arranged for actuation in a counterclockwise direction from the position shown in Fig. 20 by an appropriately set storage plunger as such storage plunger moves into station V of the storage drum 581, and this is accomplished by providing an extension 645E on such lever as will be evident in Fig. 20 of the drawings. A storage plunger that has been set in response to the sensing of a tab T—1, T—2, T—3 or T—4 is arranged to accomplish such actuation of the lever 645, and the arrangement is such that the lever 645 will be maintained in its actuated position so long as the particular storage plunger remains in station V of the storage drum 581.

The cam plate 648—2 is arranged to be rocked in a counterclockwise direction by an appropriately set storage plunger 580 as such storage plunger moves from station V to station VI of the storage drum, and to be maintained in such actuated position so long as the particular storage plunger remains in station VI. Thus the cam plate 648 has a cam surface 648X formed thereon as will be evident in Figs. 20 and 27, and this cam surface is so arranged that it will be engaged by the beveled leading corner of the cam of the storage plunger 580 almost immediately upon initiation of an indexing movement of the storage drum 581 in which such storage plunger is to be indexed from station V to station VI of the storage drum. The cam lobe 580C of the storage plunger then moves under a dwell surface 648D so as to maintain the cam plate 648—2 in its actuated position so long as the particular storage plunger remains in station VI of the storage drum. Immediately upon initiation of the next indexing movement of the storage drum, the particular storage plunger rides out of engagement with respect to the dwell surface 648D, and the cam plate 648—2 returns to its normal position in which the switch 603 is opened.

The cam plate 648—3 has similarly disposed surfaces 648X and 648D, but the surface 648D in this instance merges with a slot 648S that is formed in an extension 648E of the cam plate 648—3 as will be evident in Fig. 28 of the drawings. At its right hand end, the slot 648S terminates in a cam surface 648X—2 which is so dis-

posed that this cam surface will be engaged by the beveled leading corner of a cam of an appropriately set storage plunger 580 as this storage plunger starts its movement between stations VI and VII of the storage drum. The storage plunger then moves into engagement with a dwell surface 648D—2 so that the cam plate 648—3 will be maintained in its actuated position so long as the particular storage plunger remains in station VII of the storage drum. The extent of the dwell surface 648D—2 is such that the cam plate 648—3 will be released for return to its normal rest position soon after the next indexing movement of the storage drum 581 is initiated.

The cam plate 648—4 has similarly formed and disposed surfaces 648X, 648D, 648X—2 and 648D—2, but the surface 648D—2 terminates in a slot 648S—3 which allows the cam plate 648—4 to return to its normal position when a cooperating storage plunger is advanced out of station VI. Almost immediately however such a storage plunger encounters a cam edge 648X—3 so as to again rock the cam plate 648—4 to its switch closing position, and such a plunger then rides along a dwell surface 648D—3 so as to maintain the cam plate 648—4 in its actuated position so long as the particular storage plunger remains in station VIII of the storage drum. As soon as the next indexing movement of the storage drum is initiated, the particular storage plunger rides out of engagement with respect to the dwell surface 648D—3 so as to thereby allow the cam plate 648—4 to return to its normal position.

It has been mentioned hereinbefore, that certain of the transmitting levers 640 are effective to selectively operate the switches 660, and this selective operation of the switches 660 is utilized under the present invention to cause the machine to be stopped when an insufficient number of lines remains on the sheet S to accommodate all of the follower plates of the next group of printing devices from which impressions are to be made. Thus as will be evident in Fig. 30 of the drawings, the switch 660—2 has a pin 670—2 disposed in such a position that this pin 670—2 will be engaged by the transmitting lever 640—2 when such transmitting lever is rocked through its operative stroke in a counterclockwise direction. Such operative engagement of the transmitting lever 640—2 with the pin 670—2 serves to close the switch 660—2. Similar pins 670—3 and 670—4 are associated respectively with the switches 660—3 and 660—4 so that these switches may be selectively closed in operative movements of the transmitting levers 640—3 and 640—4.

The switches 660 are operatively related to switching means 675, Fig. 30, that are operatively related to the operating rack 416 of the lister, and such switching means 675 are set in different operative positions in accordance with the number of lines remaining on the sheet S when such sheet is approaching the position wherein impressions will be made in the last few lines thereof. The switch means 675 has a movable switch contact 676 and has three stationary contacts 677—2, 677—3 and 677—4. The movable contact 676 of this switch is operatively connected by a pin and slot connection 678 to an operating lever 679 which is pivoted on the lister carriage at 680 adjacent one side edge 681 of the operating rack 416, and a tooth 679T of the operating lever 679 is urged into an engagement with the adjacent edge surface of the rack 416 by spring means 683. The engagement of the tooth 679T with the edge surface 681 of the rack 416 maintains the switch

member 676 out of engagement with the stationary contacts of the switch until the paper holder 412 is moved into position for printing in the fourth line from the bottom of the sheet, and when the paper holder 412 is moved into this position it will be apparent that the impression from the next printing device will necessarily be made in the third line from the bottom of the sheet S. To afford an indication of this condition, a cut away surface 485-3 is provided on the rack 416 in such a position that it moves into position opposite the tooth 679T when the paper is moved into the aforesaid position, thereby to allow the lever 679 to move or rock to the left in Fig. 30. This shifts the contact 676 into engagement with the contact 677-3. Similarly, the movement of the paper holder 412 so as to dispose the third line from the bottom of the sheet in printing position moves a further cut away surface 485-2 into alignment with the tooth 679T, and this allows the movable member 676 of the switch to move into engagement with the switch 677-2 as well as the switch contact 677-3. When the paper holder 412 moves to such a position as to locate the next to the bottom line of the sheet S opposite printing position, a further cut away surface 485-1 moves into alignment with the tooth 679T, and this allows the movable member of the switch to move to such a position that it engages the contact 677-1 as well as the contact 677-2 and 677-3.

Thus the position of the switch member 676 indicates the number of lines that remain at the bottom of the sheet S, while the selective closure of the switches 660 serve to indicate the number of printing devices that are included in the next group that is to be printed, and these indications are utilized to stop the machine in the event that the number of lines remaining on the sheet S is insufficient to accommodate all of the printing devices of the group. Thus the stop solenoid 113 has one of its terminals connected by wires 690 and 691 in series to the wire 606, while wires 692 and 693 in series connect the other terminal of the solenoid 113 to one contact of a switch 695-1 of a relay 695. Wires 696 and 697 are extended in a series from the other contact of the switch 695-1 to the wire 619 so that upon closure of the switch 695-1, the stop solenoid 113 will be energized and the machine will be stopped. In this connection it may be observed that one or more switches 698 may be connected in parallel to the switch 695-1 for energizing the stop solenoid 113 in response to other undesired conditions detected in the machine, as described in detail in my aforesaid Patent No. 2,359,854. One such switch 698 is disclosed herein in Fig. 30, one contact of this switch being connected to the wire 697 while the other contact switch 698 is connected by wire 699 to the wire 692.

In affording an energizing circuit for the relay 695, a wire 700 is extended from the wire 691 to one terminal of the relay, and a wire 703 extends from the other terminal of the relay to the movable switch contact 676. The circuit to the contact 676 from the other side of the electrical source 605 is of course completed through selective closure of the switches 660 and by connections extended therefrom to the several stationary contacts 677. Thus a wire 703 is extended from the wire 611, and has branch leads 704 extended respectively to one of the contacts of each of the switches 660. A wire 705 is extended from the other contact of the switch 660-2 to the stationary contact 677-1; a wire 706 is extended

from the other contact of switch 660-3 to the stationary contact 677-2; while a wire 707 is extended from the other contact of the switch 660-4 to the stationary contact 677-3. These circuit connections are effective in a manner to be described hereinafter to energize the relay 695 when an insufficient number of lines remains on the sheet S to accommodate all of the printing devices in a group, and this causes the stop solenoid 113 to be energized so as to stop the machine. It will be recognized that operation of the relay 695 may take place when the sheet S is positioned with the fourth line from the bottom thereof disposed at printing position, and hence the stopping of the machine under such conditions may not indicate promptly to the operator that a new sheet S should be mounted in the paper holder 412. For this reason, an indicating signal lamp 710 is provided that is under the control of the relay 695. Thus a wire 711 is extended from the wire 691 to one terminal of the signal lamp 710, while a wire 712 extends from the other terminal of the lamp 710 to one contact of a switch 695-2 of the relay 695. A wire 713 is extended from the other contact of the switch 695-2 to the wire 696 so that when the relay 695-2 is operated, the signal lamp 710 will be lighted. It will be evident of course that the signal lamp 710 will not be operated in the ordinary stopping at the end of the sheet S, such normal stopping being attained by means including a control opening 715 formed in the flexible rack 416, as described in my aforesaid Patent 2,359,853.

Operation

In the operation of the present machine, the printing devices D are loaded into the magazine M, and the first sheet S of the tax roll is placed in position in the paper holder 412 of the lister 400. The paper holder 412 of the lister is of course shifted to its forward position so as to be located for printing of the impressions from the first printing device in the first line of the sheet. The main drive motor of the machine is then started into operation by withdrawal of the control plunger 110 on the forward control panel, and actual printing operation of the machine is then initiated by withdrawal of the auto-stop control plunger 112 of the machine. When the machine operation is started, the sheet S is located in the right hand position illustrated in Fig. 2 of the drawings, but during the first cycle of operation of the machine, the lister cam 425 operates through one half of a revolution to shift the carriage 408 of the lister to its left hand position, and in the course of such movement of the lister carriage, the cam 421 operates on the pawl carrier 418 to advance the sheet S into such a position that the impression from the plate 151 of the first printing device will be made in the first column of the sheet S. In the next cycle of operation of the machine, the lister carriage 408 is shifted back to the right hand position of Fig. 60 2 and in the course of such movement the back spacing cam 420 operates to back space the sheet S in an amount sufficient to cause the printed impression from the plate 152 of the printing device to be made in the same line of the second column. The numbering mechanism 515 will in such an instance be effective to print the item or serial number 155 in the third column of the first line of the sheet S.

The foregoing general discussion of the operation of the machine will serve as a basis for spe-

cific consideration of the various types of cycles through which the machine may be operated under control of the tabs or identifying means carried on the lead printing device and on the individual printing devices. Thus if it be assumed that an individual printing device having the shiftable tab PS disposed in the skip position is disposed at sensing station II, the downward sensing movement of the sensing head H will cause the sensing pin 575S to engage the tab PS, and when this occurs the sensing head H will be stopped at its highest sensing level with a result that the storage plunger 580 which is then at the station II of the storage drum will be moved from the restored position to the skip position indicated in Fig. 23 of the drawings. The storage plunger 580 that has thus been set in the skip position will be advanced in timed relation to the advancing movements of the printing device from which such sensed indication was derived so that this sensing plunger 580 will be moved into station IVT of the storage drum in the same cycle in which the related printing device is moved into station IVT of the printing device guideway. It will be recalled that when a printing device is thus disposed in station IVT of the printing device guideway, it will, in the next cycle of operation of the machine be moved into printing station V of the machine. Thus in the cycle of machine operation which precedes such movement of the particular printing device into printing position, the related storage plunger 480 will move into station IVT of the storage drum and will actuate the transmitting lever 640S. Hence the cam 640A will act to close the switch 601, and it should be observed in this regard that the switch 601 will remain closed until such time as the restoring plunger 601P is actuated. Such closure of the skip switch 601 will cause the skip solenoid 473 to be energized so that in the next cycle of machine operation the platen clutch 460 will be held disengaged. The lister control solenoid 445, of course, remains energized, so as to prevent engagement of the lister clutch 426, and this insures that the paper carriage 412 of the lister will be maintained in the same lateral position and the timing thereof will not be disturbed. Thus the individual printing device from which the sensed indication has been taken will be moved into printing position, but an impression will not be made therefrom. In the course of such advancing movement of the particular individual printing device in the printing position, the storage drum 580 is of course indexed to bring the next storage plunger into station IVT of the storage drum.

Assuming that the next storage plunger has been set into the skip position indicated in Fig. 23 by the tab PS of the lead printing device of a group, it will be apparent that the action will be the same as hereinbefore described as to such lead printing device as it is moved into printing position. With respect however to the follower printing devices of the group as they are moved into printing position in succeeding cycles of operation of the machine, it should be recalled that the skip switch 601 remains in its closed position until the restoring plunger 601P thereof is actuated, and such actuation of the restoring plunger 601P can be accomplished only by a storage plunger 580 that has been set to be aligned with one of the transmitting levers 640-1, 640-2, 640-3 or 640-4. Hence all of the follower printing devices of such a group will be moved into printing position V in what may be termed skip

cycles of operation of the machine. As the last follower printing device of the group moves into the station IVT of the printing device guideway, a storage plunger that is related to the next succeeding printing device will be moved into station IVT of the storage drum.

Assuming for purposes of illustration that the next storage plunger 580 that is thus moved into station IVT of the storage drum has been set by sensing cooperation of the sensing head H with a tab T-1 of an individual printing device, such storage plunger will be operatively engaged with the transmitting lever 640-1. Hence the operative rocking movement of the lever 640-1 will actuate the pin 656 and the lever 654 so as to operate the restoring plunger 601P of the switch 601. The skip switch 601 will thus be opened, and the machine will be conditioned for normal duplicate operation in the next two cycles of machine operation. Hence in the next machine cycle, the platen P as well as the printing device advancing mechanism will be operated, and moreover, the advancing movement of the particular storage plunger 580 out of station IVT early in this next cycle will rock the wide lever 645 so as to thereby open the normally closed lister control switch 602 and permit the desired lateral shifting movement of the lister carriage. The platen roller PR will of course be set so as to make an impression from the plate 151 of the printing device in the first column of the sheet S. Because the particular storage plunger 580 is still engaged with the lever 640-1 in position V of the storage drum, the switch 602 will be retained in its open position throughout the cycle of machine operation that has just been described, and the lister carriage 408 will therefore be shifted in the next cycle of operation of the machine to its right hand position so that the impression made from the plate 152 of the printing device will be made in the second column of the sheet.

Assuming that the numbering mechanism 515 has been advanced in the cycle of operation when the individual printing device was moved into printing position, the newly set number will be printed in the third column of the sheet S in the cycle when the impression is made from the printing plate 152 in the second column.

It will be recognized that during such second cycle with respect to the aforesaid individual printing device, the action of the duplicator mechanism 484-485 will maintain the printing device advancing means inactive so that the storage drum 580 will also remain at rest. However, in the cycle of machine operation when the aforesaid individual printing device was moved into printing position, a new storage plunger 480 will have been moved into position IVT of the storage drum.

Assuming that the new storage plunger which has thus been moved into station IVT of the storage drum is one which has been set due to sensing cooperation of the sensing head H with a tab T-2, the cam lobe 580C of such new storage plunger will have been engaged with the transmitting lever 640-2. Thus the switch 660-2 will have been closed, and the pin 656 will have been engaged so as to operate the restoring lever 652 of the switch 601. Such operation of the lever 652 will in such an instance be without effect since the switch 601 is already in its open or restored condition. Thus in the next cycle of machine operation, the printing operation, including the operation of the automatic platen

setting mechanism, the advancing movements of the printing device advancing means and the lateral shifting movements of the lister carriage will progress and take place in the same manner as hereinbefore described with respect to an individual printing device. At the end of the machine cycle in which the second impression is made from the lead printing device, the related storage plunger 580 will be disposed at station V of the storage drum, and upon initiation of the next cycle of machine operation after the one in which the second impression is made from the lead printing device, the cam 580C of this storage plunger will, at the very beginning of the machine cycle, be moved out of engagement with respect to the wide lever 645 so as to thereby allow the switch 602 to be opened. This prevents lateral shifting movement of the carriage 408 of the lister and retains the second column of the sheet S in alignment with printing position. At substantially the time when the wide lever 645 is thus released, the cam of the related plunger 580 engages the cam surface 648X of the cam plate 648-2, thereby to rock this plate in a counterclockwise direction Fig. 20, and thereby close the control switch 603. This serves to energize the numbering machine control solenoid 535, thereby to shift the numbering machine to its lower or inactive position, and in this connection it will be noted that the advancing plunger 541 of the numbering machine will under such circumstances be so positioned that the numbering machine will remain at the same setting. The closure of the control switch 603 also serves to energize the platen control solenoid 560 which acts to shift the pawl 557 to its inactive position, and hence the setting of the platen roller PR will remain unchanged, and the next impression will be made from the plate 152 of the follower printing device.

The closure of the switch 603 also serves to energize the duplicator control solenoid 510 which operates to shift an actuating pawl 487 to its inactive position, and as a result the follower printing device will remain at printing position for the performance of but one printing operation therefrom.

Closure of the control switch 603 as aforesaid also serves to close an energizing circuit to the line spacer motor 423 of the lister which operates through its cam 424 to impart a line spacing movement to the line spacing pawl carrier 418 which, in turn, causes the paper carriage 412 to be advanced or line spaced in such a way that the impression made from the follower printing device will be made in the next line of the sheet S. At the end of the machine cycle in which an impression is made from the follower printing device, the related storage plunger 580 will be disposed in station VI of the storage drum, and the storage plunger 580 that is disposed at station V of the storage drum will be one that has been moved beyond its effective positions, so that it will not be effective in any way upon the lever 645.

Since it is the storage plunger that is related to the follower printing device, a new storage plunger 580 will of course be disposed at station IVT of the storage drum, and for purposes of illustration it will be assumed that this new storage plunger is one that has been set in response to the sensing of a tab T-3. Thus the cam lobe 580C of the new storage plunger will be aligned with, and at this time will be effective upon, the transmitting lever 640-3. Thus

the switch 660-3 will be closed at this time, and the restoring lever 652 will be in its actuated position. In the next machine cycle, this particular storage plunger will act in the manner hereinbefore described on the lever 645, and the machine will operate through two cycles so as to make two impressions from the lead printing device in the same manner as hereinbefore described with respect to the other lead printing device. The numbering machine and the lister will of course operate in the manner hereinbefore described, and after the second impression from the lead printing device, the machine will enter upon another printing cycle in which the side or lateral shifting mechanism of the lister 400 will be rendered inactive because of the release of the lever 645, and the control cam 648-3 will be actuated so as to accomplish all of the functions hereinbefore described with respect to the cam plate 648-2. Upon completion of the printing operation with respect to the first follower printing device, the related storage plunger will engage the cam surface 640X-2 of the cam plate 648-3, and hence the switch 603 will again be closed so as to cause the related functions to take place, and thereby cause an impression to be made from the second follower printing device in the next line of the second column of the sheet S.

30 A similar action takes place in respect to the group of printing devices that includes a lead printing device and three follower printing devices, with the exception however that the related storage plunger 580 is set for cooperation with the transmitting lever 640-4 and the cam plate 648-4. The only difference in operation, however, is that the control switch 603 is closed for an additional machine cycle so that an impression is made from the third follower printing device.

It has been pointed out hereinbefore that the switches 660 are closed selectively in accordance with the number of printing devices in each group, and when the position of the paper holder 412 is such that sufficient lines are not available on the sheet S to accommodate all of the printing devices in such a group, the switch means 675 is set in response to the longitudinal position of the flexible rack 416 so as to cooperate with the switches 660 and cause the relay 695 to be actuated so as to stop the machine and cause the signal lamp 710 to be lighted.

Conclusion

55 From the foregoing description it will be apparent that the present invention enables tax roll printing to be accomplished through the use of a relatively simple printing apparatus the basic elements of which are of a standard and 60 widely used construction so as to facilitate manufacture as well as repair and service problems. Moreover, the tax roll printing accomplished under the present invention involves a simplified tabbing of the printing devices, and the arrangement is such that tabs carried by the lead printing devices of groups thereof serve to control a plurality of cycles of machine operation so that proper machine operation is attained as to all of the follower printing devices even though such 65 follower printing devices are not tabbed or otherwise identified.

Another outstanding feature of the present invention is found in the automatic correlation of the sensing means with the position of the paper holder so that printing operations may progress

at the normal high speed, and without intermediate delays, until the sheet has been filled or until a condition is encountered where insufficient lines remain on the sheet to accommodate all of the printing devices of the next group.

The illustrative embodiment of the machine of the present invention is, of course, adapted for use with groups of printing devices containing a maximum of three follower printing devices, but it will be recognized that under the invention provision may be made for larger capacity or larger groups in the event that this is desirable. However, for most tax roll work, the capacity of the illustrated machine is adequate, and in those rare instances where more than three follower printing devices are required, such large groups will be separately filed so that they may be printed while the machine is being operated under manual rather than automatic control.

Thus, while I have illustrated and described the preferred embodiment of my invention, it is to be understood that it is capable of variation and modification and I, therefore, do not wish to be limited to the precise details set forth, but desire to avail myself of such changes and alterations which fall within the purview of the following claims.

I claim:

1. In a printing machine through which groups of lead and follower printing devices may be passed in a step by step manner such that the printing devices come to rest successively at printing position in the machine, impression means operable to produce printed impressions from such printing devices at printing position, each of said lead printing devices of each of said groups thereof having identifying means positioned thereon in an identifying position indicative of the number of printing devices in its respective group, lister mechanism associated with said machine and adapted to impart spacing movements to a sheet with respect to printing position in the machine, stop means for stopping the operation of said machine, selector mechanism embodying sensing means for sensing the identifying means of the printing devices, said selector means being constructed and arranged to sense such identifying means on a lead printing device to determine the number of printing devices included in each group, sensing means associated with said lister to sense the number of lines remaining on each sheet, comparing means operable under the joint control of both of said sensing means to compare the same with the number of printing devices in the next group of printing devices from which impressions are to be made, and means operable under control of said comparing means upon said stop means to stop said machine when the number of lines remaining on the sheet is insufficient to receive the impressions from all of the printing devices of the next group.

2. In a printing machine through which groups of related lead printing devices having printing means in first and second areas thereof and follower printing devices having printing means only in second areas thereof, and individual printing devices having printing means in first and second areas thereof and unrelated to but interspersed between such groups, may be passed in a step by step manner such that the printing devices come to rest successively in printing position in the machine, impression means operable to produce printed impressions from printing devices disposed in printing posi-

tion and constructed and arranged for selective adjustment to different relationships wherein printed impressions are made selectively from said first or second areas of the printing devices,

5 each of said lead printing devices of each of the groups thereof having identifying means positioned thereon in identifying positions respectively indicative of the number of printing devices in the related group, and each of said individual printing devices having identifying means thereon in a predetermined identifying position to indicate that such printing device is not related to a group of printing devices, a two-column lister embodying means operable in normal lister cycles to impart related column shifting, line spacing and back spacing movements to a sheet carried by such lister, independently operable line-spacing means embodied in said lister for imparting line spacing movements to 10 such a sheet, means normally operable to advance printing devices in the machine in alternate cycles of said impression means, normally inactive means for causing operation of said two-column lister through a cycle of operation 15 in each operation of said impression means, selector means operable to sense the identifying means of the printing devices as they pass through the machine, means under control of said sensing means and operable to govern and 20 modify the operation of said lister, of said impression means and of said printing device feeding means in accordance with the identifying means sensed upon said printing devices, stop means for stopping said machine, sensing means 25 associated with said lister to sense the number of lines remaining on each sheet, comparing means operable under the joint control of said sensing means to compare the same with the number of 30 printing devices in the next group of printing devices from which impressions are to be made, and means operable upon said stop means under control of said comparing means to stop said machine when the number of lines remaining on the sheet is insufficient to receive the impressions 35 from all of the printing devices of the next group.

3. In a printing machine through which groups of lead and follower printing devices may be passed in a step by step manner such that the printing devices come to rest successively at printing position in the machine, impression means operable to produce printed impression from such printing devices at printing position, each of said lead printing devices of each of said 40 groups having identifying means positioned thereon in an identifying position indicative of the number of printing devices in its respective group, lister mechanism associated with said machine and adapted to impart spacing movements 45 to a sheet with respect to printing position in the machine, stop means for stopping the operation of said machine, selector mechanism embodying sensing means for sensing the identifying means of the printing devices, said selector 50 means being constructed and arranged to sense the identifying means of each lead printing device to determine the number of printing devices included in each group, sensing means associated with said lister to sense the number of lines remaining on each sheet, comparing means under control of both of said sensing means and operable to compare the sensed number of lines with the number of printing devices in the next group 55 of printing devices from which impressions are to be made, stop means for said machine operable 60

under control of said comparing means to stop said machine when the number of lines remaining on the sheet is insufficient to receive the impressions from all of the printing devices of the next group, and indicating means rendered operable when said machine has been stopped under control of said comparing means.

4. In a printing machine through which groups of related lead and follower printing devices, and individual printing devices unrelated to but interspersed between such groups, may be passed in a step by step manner such that the printing devices come to rest successively in printing position in the machine, impression means operable to produce printed impressions from such printing devices at printing position, each of said lead printing devices of each of the groups thereof having identifying means positioned thereon in identifying positions indicative of the number of printing devices in its respective group, and each of said individual printing devices having identifying means thereon in a predetermined identifying position indicate that such printing device is not related to a group of printing devices, a lister embodying means for imparting shifting movements to a sheet carried by such lister, means for advancing printing devices in the machine, means for controlling operation of said lister, selector means including sensing means operable to sense the identifying means of the printing devices as they pass through the machine, means under control of said sensing means and operable to modify the operation of said lister and of said printing device advancing means in accordance with the identifying means sensed upon said printing devices, stop means for stopping said machine, sensing means associated with said lister to sense the number of lines remaining on each sheet, comparing means operable to compare this number with the number of printing devices in the next group of printing devices from which impressions are to be made, and means controlled by said comparing means and operable upon stop means to stop said machine when an insufficient number of lines remain on the sheet to receive the impressions from the next group of printing devices.

5. In a printing machine through which groups of related lead and follower printing devices may be passed in a step by step manner such that the printing devices come to rest successively in printing position on the machine, impression means operable to produce printed impressions from such printing devices at printing position, identifying means on certain of the printing devices whereby the number of printing devices in each respective group may be determined, a lister embodying means for imparting shifting movements to a sheet carried by such lister, means for advancing printing devices through the machine, means for controlling operation of said lister, selector means including sensing means operable to sense the identifying means of the said certain printing devices as they pass through the machine to determine the number of printing devices in each group, means under control of said sensing means and operable to modify the operation of said lister and of said printing device feeding means in accordance with the identifying means sensed upon said printing devices, stop means for stopping said machine, sensing means associated with said lister to sense the number of lines remaining on each sheet, comparing means operable under the joint control of both of said sensing means to compare

this number with the number of printing devices in the next group of printing devices from which impressions are to be made, and means operable upon said stop means under control of said comparing means to stop said machine when an insufficient number of lines remain on the sheet to receive the impressions from the next group of printing devices.

6. In a printing apparatus through which groups of varying numbers of related lead and follower printing devices may be passed in a step by step manner such that the printing devices come to rest successively at printing position in the machine, impression means operable to produce printing impressions from printing devices at printing position, the lead printing device of each of said groups thereof having identifying means positioned thereon in a selected identifying position indicative of the number of printing devices in its group, a two-column lister for feeding sheets to printing position, a plurality of selectively operable actuating devices for said two-column lister operable to actuate said sheet lister through two-column listing movements or through single-column listing movements relative to said printing position, operative means for selecting the actuating devices that are to be effective, independent cyclic control means for each size of group which may be passed through the printing apparatus, and each operable to control the apparatus for a number of machine cycles determined by the number of printing devices included in the size of group to which it is allocated, control means associating the respective cyclic control means with said operative means for governing operation thereof, operating means selectively settable to actuate any selected one of said cyclic control means, sensing means for sensing the identifying means on said printing devices, and means governed by said sensing means to set said operating means to operate the cyclic control means selectively in accordance with the number of printing devices in the respective groups.

7. In a printing apparatus through which groups of varying numbers of related lead and follower printing devices may be passed in a step by step manner such that the printing devices come to rest successively at printing position in the machine, impression means operable to produce printing impressions from printing devices at printing position, the lead printing device of each of said groups thereof having identifying means positioned thereon in a selected identifying position indicative of the number of printing devices in its group, a two-column lister for shifting and advancing sheets relative to printing position, first and second selectively operable actuating means for said lister, the first of which is operable to impart normal two-column listing movements to a sheet and the second of which is operable to impart single column listing movements to a sheet, operative means for selecting the actuating means that are to be effective, a common governing means adapted to cooperate with said operative means to cause operation of said first actuating means, independent cyclic control means for each size of group which may be passed through the printing apparatus and each operable to control the apparatus for a number of machine cycles determined by the number of follower printing devices included in the size of group to which it is allocated, control means associating the respective cyclic control means with said operative means

for causing operation of said second actuating means whenever a follower printing device is located at printing position, operating means selectively settable to actuate said common governing means and any selected one of said cyclic control means, sensing means for sensing the identifying means on said printing devices, and means governed by said sensing means to set said operating means to operate the cyclic control means selectively in accordance with the number of printing devices in the respective groups.

8. In a printing apparatus having a plurality of operative mechanisms and through which groups each consisting of a lead printing device and varying numbers of related follower printing devices may be passed in a step by step manner to printing position in the machine, the lead printing device of each of said groups thereof having identifying means positioned thereon in a selected identifying position indicative of the number of printing devices in its group, independent cyclic control means for each size of group which may be passed through the printing apparatus, and each operable to control said operative mechanisms of the apparatus for a number of machine cycles related to the number of follower printing devices included in the size of group to which it is allocated, operating means selectively settable in different control positions to actuate any selected one of said cyclic control means, sensing means for sensing the identifying means on said printing devices, means governed by said sensing means to set said operating means in different control positions to operate the cyclic control means selectively in accordance with the identifying means sensed by said sensing means, and other control means for one of said mechanisms arranged for actuation by operating means only when said operating means are set in still another position.

9. In a printing machine having a plurality of operative mechanisms and through which machine a series of printing devices each adapted to bear identifying means at one or more selected identifying positions thereon are adapted to be passed to a sensing station in the machine, sensing means at said sensing station for sensing such identifying means, a storage drum having a plurality of storage plungers mounted thereon in peripherally spaced relation and for longitudinal set-up movement from an initial position to any selected one of a plurality of set up positions, means for indexing said drum in each machine cycle, means operable under control of said sensing means to set said storage plungers one by one to set-up positions determined by said sensing means, a plurality of shiftable control members operatively associated with said operative mechanisms for controlling the operation of said operative mechanisms in accordance with shifting movements imparted to said control members, said control members being disposed in a plurality of different groups about said drum as to be selectively actuated by said plungers in accordance with the rotative position of said plungers on said drum and in accordance with the positions to which said plungers are set, and arms on certain of said control members extended partially about said drum and arranged for operative engagement by an appropriately set plunger in a plurality of machine cycles.

10. In a printing machine having a plurality

of operative mechanisms and through which machine a series of printing devices each adapted to bear identifying means at one or more selected identifying positions thereon are adapted to be passed to a sensing station in the machine, sensing means at said sensing station for sensing such identifying means, a storage drum having a plurality of storage plungers mounted thereon in peripherally spaced relation and for longitudinal set-up movement from an initial position to any selected one of a plurality of set up positions, means for indexing said drum in each machine cycle, means operable under control of said sensing means to set said storage plungers one by one to set-up positions determined by said sensing means, a plurality of shiftable control members operatively associated with said operative mechanisms for controlling the operation of said operative mechanisms in accordance with shifting movements imparted to said control members, said control members being disposed in such positions as to be selectively actuated by said plungers in accordance with the positions to which said plungers are set, arms on said control members extended partially about said drum and having cam surfaces thereon formed and arranged for operative engagement by an appropriately set plunger in a plurality of machine cycles to impart shifting movements to said control members in at least certain machine cycles, and other control members operatively connected to certain of said mechanisms and arranged to be actuated by plungers in other machine cycles.

11. In a printing machine having a plurality of operative mechanisms and through which machine a series of printing devices each adapted to bear identifying means at one or more selected identifying positions thereon are adapted to be passed to a sensing station in the machine, sensing means at said sensing station for sensing such identifying means, a storage drum having a plurality of storage plungers mounted thereon in peripherally spaced relation and for longitudinal set-up movement from an initial position to a selected set position, means for indexing said drum in each machine cycle, means operable under control of said sensing means for setting said storage plungers, a plurality of shiftable control members having normal positions and control positions to which they may be shifted, means associating each of said control members with at least one of said operative mechanisms to govern operation thereof when said control members are shifted to said control positions, means on said control members affording a plurality of cam surfaces adapted to be successively engaged in successive machine cycles by a storage plunger located in a related set position to thereby shift said control member to its control position in a plurality of machine cycles under the control of identifying means on a single printing device, and another control member disposed for cooperation with and actuation by storage plungers in other rotative positions of said drum.

12. In a printing machine having a plurality of operative mechanisms and through which machine a series of printing devices each adapted to bear identifying means at one or more selected identifying positions thereon are adapted to be passed to a sensing station in the machine, sensing means at said sensing station for sensing such identifying means, a storage drum having a plurality of storage plungers mounted thereon

in peripherally spaced relation and for longitudinal set-up movement from an initial position to any selected one of a plurality of set up positions, means for indexing said drum in each machine cycle, to move said plungers successively into a plurality of control stations, means operable under control of said sensing means to set said storage plungers one by one to set-up positions determined by said sensing means, a first plurality of shiftable control members disposed at a first one of said control stations, another control member disposed at another of said control stations, a second plurality of shiftable control members disposed at a third one of said control stations, means operatively associating each of said control members with at least one of said operative mechanisms for controlling the operation of said operative mechanisms in accordance with shifting movements imparted to said control members, said plurality of control members at said first and third control stations being disposed in such positions as to be selectively actuated by said plungers in accordance with the positions to which said plungers are set, and arms on certain of said control members at said third control station extended partially about said drum and arranged for operative engagement by an appropriately set plunger in a plurality of other control stations.

13. In a printing machine having a plurality of operative mechanisms and through which machine a series of printing devices each adapted to bear identifying means at one or more selected identifying positions thereon are adapted to be passed to a sensing station in the machine, means for advancing printing devices through the machine, sensing means at said sensing station for sensing such identifying means, a storage drum having a plurality of storage plungers mounted thereon in peripherally spaced relation and for longitudinal set-up movement from an initial position to any selected one of a plurality of set up positions, means for indexing said drum to different control stations in each cycle of operation of said advancing means, means operable under control of said sensing means to set said storage plungers one by one to set-up positions determined by said sensing means, a plurality of sets of shiftable control members disposed at different control stations about said

50

drum and operatively associated with said operative mechanisms for controlling the operation of said operative mechanisms in accordance with shifting movements imparted to said control members, said control members being disposed in such positions as to be selectively actuated by said plungers in accordance with the positions to which said plungers are set, arms on certain of the control members at one of said stations extended partially about said drum and having cam surfaces thereon formed and arranged for operative engagement by an appropriately set plunger in a plurality of machine cycles to impart similar shifting movements to said certain control members in at least certain machine cycles.

14. A two-column lister embodying means operable in normal lister cycles to impart related column shifting, line spacing and back spacing movements to a sheet carried by such lister to attain a two-column listing operation of the lister, independently operable line-spacing means embodied in said lister for imparting line spacing movements to such a sheet to attain a single-column listing operation of the lister, governing means controlling said first mentioned means for causing said lister to operate selectively through single-column or two-column listing operations, and numbering mechanism controlled by said governing means to make a serial numbering impression each time said lister operates through a two-column listing operation and to prevent operation of said numbering mechanism whenever said lister operates through a single-column listing operation.
